United States Patent Office

Des. 227,840
Patented July 24, 1973

227,840

ARMOIRE WITH CARVED MOTIF OR THE LIKE

Joseph E. Adkinson, 3807 Leland St.,
Chevy Chase, Md. 20015

Filed Feb. 4, 1972, Ser. No. 223,820

Term of patent 14 years

Int. Cl. D6—04

U.S. Cl. D6—154

The single figure is a view in perspective of my design.

The back of the armoire is conventionally flat and the side not pictured is identical to the side shown.

I claim:

The ornamental design for an armoire with carved motif or the like, substantially as shown and described.
